UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 17,842, dated November 1, 1887.

Application filed September 21, 1887. Serial No. 250,352. Term of patent 3½ years.

To all whom it may concern:

Be it known that I, HENRIETTA F. DUKE, of the city, county, and State of New York, have invented and produced a new and original Design for a Pattern of a Lady's Basque; and I do hereby declare that the engraved prints accompanying this specification convey to any one accustomed to using paper patterns a clear understanding of how a garment made up by the pattern will appear.

The design shows fronts that are close fitting below the bust, have a surplice fullness at the shoulders, and flare from the bust to the shoulders, exhibiting a pointed vest between them; a close fitting back that exhibits four lapping loops of different lengths at either side of the

center below the waist-line, a standing collar, and coat-sleeves displaying plaited puffs upon them to below the elbows. The lower outline of the basque describes two points in front, a high curve at the sides, and a point at either side of the loops.

What I claim as my invention, and desire to secure by Letters Patent, is—

The design for a lady's basque, as shown in the engraved prints accompanying this specification.

HENRIETTA F. DUKE.
